UNITED STATES PATENT OFFICE

HARVEY HUBBELL, JR., OF BRIDGEPORT, CONNECTICUT

CAP AND SHELL FASTENING

Application filed May 28, 1929. Serial No. 366,624.

This invention relates to the enclosing shell for lamp sockets and the like, particularly to the means for connecting the cap and body sections of the shell together, and has 5 for an object to provide an improved cap and shell construction which will give a smooth plain exterior to the cap and in which the body and skirt portions of the cap may be made in one piece. 10 It is also an object of the invention to provide an improved construction which will positively lock the cap and body sections of the shell together with a connection which will carry considerable weight, but which 15 may be easily unlocked to permit separation of the cap and body.

It is a further object of the invention to provide a cap having a protected and sharply defined locking shoulder as contrasted 20 with the prior art wherein said portion is unprotected and hence is not sharply defined, and thus the present invention provides a better and more durable device and one in which the locking means between the cap 25 and shell will sustain a greater strain without failing or separating.

With the foregoing and other objects in view, I have devised the construction illustrated in the accompanying drawing forming 30 a part of this specification.

In this drawing

Fig. 1 is a side elevation of a lamp socket with portions of the cap and body section broken away to show the connections between the cap and body in section, the section being substantially on line 1—1 of Fig. 2.

Fig. 2 is a transverse section substantially on line 2—2 of Fig. 2 and showing the insulating body for mounting the switch and lamp contacts in elevation.

Fig. 3 is a partial side elevation and partial section of the cap indicating the deep and shallow notches formed in the edge of the skirt.

Fig. 4 is a perspective view of the lower part of the cap showing the free edge portions between the deep notches folded toward the inner side of the cap.

Fig. 5 is a perspective view of the upper 50 end of the body of the shell, and

Fig. 6 is a detailed section through the securing means on the plane of Fig. 1, showing the free edge beveled and on an enlarged scale.

The shell illustrated is shown as enclosing the elements of a lamp socket having a switch operated by a pull chain. The detailed construction of this switch is not shown as it forms no part of my present invention. The shell comprises a cap section 10 and a body section 11 made of sheet metal in the usual manner, and enclosed by the body section is the block 12 of insulating material in which are mounted the switch elements, not shown, and which also carries the screw shell and central lamp contacts not shown. It will, of course, be understood that while I have shown this shell connection as applied to a lamp socket, it is by no means limited to use therewith, as it may be used for enclosing shells of depending switches and like devices. This insulating block carries the usual binding post screws 13 for connecting lead wires 14 in the usual manner. The upper portion of the cap is lined with a suitable fibre or other insulating lining 15 and the body of the shell is lined with a similar lining 16 enclosing the works of the socket. The body portion of the shell also has the usual notch 17 extending longitudinally from the free end thereof for passage of the guide 18 for the pull chain 19 for operating the switch, or the key or operating the switch if a key operated switch is used.

The cap is provided with a substantially cylindrical skirt portion 20, and it is of somewhat larger diameter than the body of the cap to provide a shoulder 21 on the inside of the cap spaced a suitable distance from the free edge of the skirt. This free edge is 85 provided with deep notches 22 and shallow notches 23 at suitable regular spaced distances throughout its periphery. These notches are preferably substantially rectangular as shown. After this free edge of 90 the skirt is notched the walls 24 of the skirt between the deep notches 22 are folded over toward the body of the cap, as clearly indicated in Fig. 4, preferably toward the inner wall of the cap so that they will be out 95 100

of sight in the finished shell. It will be apparent that in this position the bottoms of the shallow notches 23 form sharply defined recessed shoulders adjacent the inner wall of the cap and spaced inwardly from the free edge of the cap, and that the portions 24 carrying these shoulders are separated by the notches 22. When this free edge is being folded over, the folding tool has a tendency to bevel the free edge as at 25, Fig. 6 making the end 25 an unsatisfactory shoulder for locking use. The shoulder at 23, however, is protected from the beveling effect of the folding tool and hence remains sharply defined with a sharp edge and forms a recessed shoulder for satisfactory locking use. It will further be noted in Fig. 4 that the deep notches have become open channels 22, and that these channels are open at both ends, while the shallow notches have provided the recessed shoulders 23. It will be also noted that it is comparatively easy in manufacture for the folding tool to fold over portions 24 between the deep notches 22.

25 The body section 11 is adapted for telescoping engagement with the cap, as shown in Fig. 1. Adjacent the free end of this section it is provided with outwardly extending lugs 26 which are preferably arranged in pairs on substantially diametrically opposite sides of this body section, one pair being adjacent the notch 17 so that the wall of the body section carrying these lugs is yieldable inwardly. This is clearly shown in Fig. 5. 30 A convenient way of forming these lugs is to form short transverse slits or cuts 27 in the body section and then force the wall of the section above the slit outwardly. This will give a shoulder 28 on the lower end of the lug which extends outwardly from the face of the body. The lugs of each pair are spaced from each other substantially the distance between two of the recessed shoulders 23 or a multiple thereof. Also between the lugs of one or both pairs is provided another outwardly extending lug or nib 29. A convenient way to form this member is to provide two spaced slits extending longitudinally of the body section and forcing outwardly the walls between the slits which provide shoulders 30 on the opposite sides of the lugs 29, and these lugs are made of a width so that they may pass into the open channels 22 between the folded portions 24 of the cap. These lugs may be of shapes other than that shown. For example, they may be similar to lugs 26 with their shoulders extending longitudinally of the shell.

60 In assembling the cap and body portions the free end of the body section is inserted in the skirt of the cap with the lugs 29 in any suitable open channels 22. The portion 31 of the body section will yield inwardly sufficient to cause the lugs 26 to pass over the portions 24, and then will spring outwardly to cause

the shoulders 28 on these lugs to engage the recessed and sharply defined shoulders 23 of the portions 24, as shown in Fig. 6, and will securely lock the cap and body sections together. The lugs 29 will preferably be seated in diametrically opposite channels 22 and the side shoulders will engage the sides of these channels to prevent relative turning movements of the cap and body sections in either direction, and so will prevent movement of the lugs or nibs 26 into alignment with the channels to permit the separation of the cap and shell. The shoulder 21 in the cap is so located as to lie adjacent the free end of the body section, as indicated in Fig. 1, to prevent this section rocking laterally in the cap and to limit movement of the body section into the cap. If it is desired to separate the cap and body section all that is necessary is to press inwardly the yieldable portion 31 which will remove the lugs 26 carried thereby from engagement with the shoulders 23. Then the body or cap may be rocked laterally to withdraw these lugs from the cap and the cap and body may be easily separated.

It will be apparent that the skirt portion of the cap is in one piece with the body portion thereof, and that a single thickness only is required, doing away with the extra enclosing ring which is now commonly employed in this type of device. This structure also gives a smooth plain outer surface to the cap, giving the required neat and attractive appearance. It will further be noted that if undue strain is placed on the cap and body sections tending to separate them, the pull of the lugs 26 on the shoulders 23 of the folded portions 24 will tend to draw these portions inwardly toward the lugs 26 and the body portion, so that instead of tending to draw away from these supporting shoulders 23 this strain tends to draw these supporting shoulders toward the base of the lugs 26 and increase the holding effect.

100 This, therefore, gives a very strong connection between the cap and body sections which will safely sustain the considerable weight involved in the shades and domes used.

Having thus set forth the nature of my invention, what I claim is:

1. A shell comprising a body section and a cap section adapted for telescoping engagement, one of said sections having its free edges provided with alternate series of shallow and deep notches, said edge being folded upon itself to provide protected shoulders and channels open at both ends, the other section being provided with laterally projecting lugs to engage said shoulders to secure the sections together, and means to enter one of said channels to prevent relative turning movements of said sections in either direction.

125 2. A socket shell comprising telescoping

cap and body sections, one of said sections having its free edge provided with a series of spaced shallow and deep notches, said free edge being folded on itself causing said notches to provide sharply defined protected shoulders and open ended channels, and the other section being provided with laterally extending lugs to engage with said protected shoulders to secure the sections together.

5 3. A shell comprising telescoping cap and body sections, said cap being provided with alternate series of deep and shallow notches in its free edge and the portion between said deep notches being folded inwardly toward the wall of the cap to provide channels open at both ends and recesses having sharply defined inner shoulders, the body being provided with laterally extending lugs to engage the shoulders in said recesses to prevent separation of the cap and body, and said body also having other laterally extending lugs to enter in certain of the channels and engage the side edges thereof to prevent relative turning movements between the cap and body.

10 4. A shell comprising telescoping cap and body sections, said cap having its free edge portion provided with a series of spaced shallow and deep notches, said free edge portion being folded on itself causing said notches to provide sharply defined recessed shoulders and open ended channels, said cap being also provided with a shoulder spaced inwardly from the free edge of said folded portion, said body section being provided with laterally extending lugs arranged to engage said recessed shoulders to secure the sections together, and the free edge of the body section being adapted to engage said spaced

15 40 shoulder in the cap to limit relative longitudinal movement of said sections.

5. A shell comprising telescoping cap and body sections, said cap section being provided with alternate series of deep and shallow notches in its free edge and the portions between said deep notches being folded inwardly on the body of the cap to provide a series of channels open at both ends and an alternate series of sharply defined recessed shoulders, said cap being also provided with a shoulder spaced inwardly from the free edges of said folded portions, said body section having laterally extending lugs to engage said recessed shoulders to secure the sections together and other lugs to engage the sides of the channels to secure the sections against relative turning movements, and the free edge of said body section being adapted to engage said spaced shoulder to limit relative longitudinal movement of said sections towards each other.

6. An enclosing shell for lamp sockets and similar devices comprising a cap having series of spaced shallow and deep notches about its free edge and the portions between said

deep notches being folded over toward the inner wall of the cap, and a body section adapted to have one end thereof inserted into said cap and carrying means to engage the free edges of said shallow notches to secure the cap and body together.

7. A shell for electrical devices comprising a cap section having series of spaced deep and shallow notches about its periphery and the portions between said deep notches folded inwardly toward the inner side of the cap to provide open channels and recessed shoulders, a body section having one end adapted to be inserted into the cap, said body section being provided with a notch leading from the end thereof providing a yieldable portion at one side thereof, said yieldable portion having a lug to engage a recessed shoulder of said folded portions, the body being also provided with another lug to engage a recessed shoulder of said folded portions on the opposite side of the cap, and an additional lug on the body adapted to enter one of said channels to prevent relative turning movements between the cap and body in either direction.

In testimony whereof I affix my signature.
